Primary Examiner—Nelson C. Holtje

(57) **CLAIM**

I claim the ornamental design for the watch-case, as shown and described.

DESCRIPTION

FIG. 1 is a front elevational view of the new ornamental watch-case of the present invention.

FIG. 2 is a rear elevational view thereof.

FIG. 3 is a right side view thereof.

FIG. 4 is a left side view thereof.

FIG. 5 is a top view thereof.

FIG. 6 is a bottom view thereof.

FIG. 7 is a right bottom perspective view thereof.

FIG. 8 is a right bottom perspective view thereof, with the watch face extended to an upright position.

FIG. 9 is a right bottom perspective view thereof, with the watch face extended to an upright position and rotated 90 degrees relative to the left side-right side axis.

FIG. 10 is a right bottom perspective view thereof, with the watch face extended to an upright position and rotated 180 degrees relative to the left side-right side axis.

FIG. 11 is a right bottom perspective view thereof, with the watch face rotated 180 degrees relative to the left side-right side axis; and,

FIG. 12 is a right top perspective view thereof, with the watch face extended to an upward position.
